UNITED STATES PATENT OFFICE.

ALEXANDER JOHNSTON, OF EDINBURGH, SCOTLAND, ASSIGNOR TO THE NORTH BRITISH RUBBER COMPANY, LIMITED, OF EDINBURGH, SCOTLAND.

FABRIC USED IN THE MANUFACTURE OF BALLOONS AND DIRIGIBLE AIRSHIPS.

1,407,197.

Specification of Letters Patent. Patented Feb. 21, 1922.

No Drawing.

Application filed September 15, 1919. Serial No. 323,966.

(GRANTED UNDER THE PROVISIONS OF THE ACT OF MARCH 3, 1921, 41 STAT. L., 1313.)

To all whom it may concern:

Be it known that I, ALEXANDER JOHNSTON, a subject of the King of the United Kingdom of Great Britain and Ireland, and whose post-office address is The North British Rubber Company Limited, Castle Mills, Fountain Bridge, Edinburgh, Scotland, have invented certain new and useful Improvements in Fabrics Used in the Manufacture of Balloons and Dirigible Airships, for which I have filed application in England Mar. 3, 1916, Patent No. 124,520 and of which the following is a specification.

Balloon and dirigible airship fabrics have hitherto been made of cotton, linen, or other textile material coated or impregnated with rubber, oil, or cellulose preparation the object of such coating being to prevent the permeation of the hydrogen or other gas, and the consequent loss of lifting power in the finished balloon or airship.

This invention has for its object to provide an improved medium for use in coating the cotton, linen, silk or other textile material in order to minimize the loss of hydrogen, and to provide a material less liable to deterioration from the action of light and more suitable generally for the purposes required in balloon and airship construction.

The present invention consists in the use of gelatine (preferably treated in any suitable or well known manner to render it insoluble in water) as a coating medium in place of, or in addition to, the hitherto known materials such as rubber, oil cellulose preparation or the like.

Under the present invention the gelatine (preferably suitably prepared as before stated) may be applied to the textile fabric by impregnating, spreading, calendering, or by any mechanical or other means, or applied in any other method suitable to the object in view.

In like manner coats of the gelatine may be applied between different plies of the textile fabric, and on the exterior or interior, with the object not only of reducing the permeation of hydrogen or other gas, but also of protecting the textile fabric from decomposition owing to the action of light and moisture, and of preventing the absorption of moisture from the atmosphere.

The proofing herein described may be applied either as an adhesive coating to the fabric, or may be prepared as a separate sheet, and applied as a lining to the fabric whether placed between two layers of fabric, or employed as a layer internal to the fabric, or in some other convenient manner.

The gelatine may be used alone, or in combination with separate layers or plies of other media such as rubber, oil, cellulose preparation, or the like, and the gelatine may be used either pure or mixed or compounded with other substances or chemicals such as pigmenting agents; or with dyeing materials; and may or may not be treated as above described to render it insoluble in water.

Alternatively the gelatine may be applied to the fabric by any of the methods stated and the fabric afterwards passed through a bath of suitable solution to render the gelatine coating insoluble in water.

The use of the gelatine as hereinbefore previously described has been found in practical experiments to reduce the loss of hydrogen gas to a negligible quantity, and to retard greatly the deterioration of the textile fabrics owing to the action of light and moisture.

We are aware that it has been heretofore proposed to coat India rubber fabric, paper or the like with gelatine which is rendered insoluble in water by one of the treatments known to the trade, and it has also been proposed to render pipes or receptacle impermeable to fluids by the use of gelatine treated in a like manner.

Claims—

1. A balloon envelope fabric comprising a plurality of textile plies and an intermediate layer of gelatine.

2. A balloon envelope fabric comprising a plurality of proofed textile plies and an intermediate layer of gelatine.

3. A balloon envelope fabric comprising a plurality of textile plies and an intermediate layer of gelatine compounded with a pigmenting agent.

4. A balloon envelope fabric comprising a plurality of textile plies and an intermediate layer of insoluble gelatine.

5. A balloon envelope fabric comprising a

plurality of textile plies, an intermediate layer of gelatine and an exterior coating of gelatine.

layer of gelatine compounded with a pigmenting agent and dyeing materials.

6. A balloon envelope fabric comprising a plurality of textile plies and an intermediate layer of gelatine compounded with dyeing materials.

The foregoing specification signed at Leith, Edinburgh, Scotland this thirteenth day of August, 1919.

ALEXANDER JOHNSTON.

In presence of two witnesses:

JOHN P. NIVEN,

DAVID P. TULLY.

7. A balloon envelope fabric comprising a plurality of textile plies and an intermediate
